ELECTRIC TRAIN SIGNALING SYSTEM

Lars O. Grondahl, Pittsburgh, Pa., assignor to
The Union Switch & Signal Company, Swiss-
vale, Pa., a corporation of Pennsylvania

Application May 6, 1930, Serial No. 450,135

25 Claims. (Cl. 246-8)

My invention relates to communication systems for railway trains, and has for an object the provision of novel means for signaling between spaced points on a train, or between two trains, or between a train and a station along the track.

The present application is a continuation in part of my copending application, Serial No. 269,148, filed April 11, 1928, for Apparatus for signaling between two points on a railroad train.

I will describe several forms of apparatus embodying my invention, and will then point out the novel features thereof in claims.

In the accompanying drawings, Fig. 1 is a diagrammatic view showing one way in which a railway train may be equipped with apparatus embodying my invention. Fig. 2 is a similar view showing another way in which a railway train may be equipped with apparatus embodying my invention. Fig. 3 is a detail view, partly diagrammatic, showing one unit of apparatus embodying my invention. Fig. 4 is a view similar to Fig. 3 but showing a modified form of the unit illustrated in Fig. 3, and also embodying my invention. Fig. 5 is a diagrammatic view illustrating the manner in which the current flows away from, and returns to, the point at which it is induced in the body of a train and in a track rail by one of the units illustrated in Fig. 3. Fig. 6 is a diagrammatic view showing two trains equipped with apparatus embodying my invention. Fig. 7 is a detail view showing a unit similar to the unit illustrated in Fig. 4, but having its inductor located in the trackway.

Similar reference characters refer to similar parts in each of the several views.

Referring first to Figs. 1 and 2, the reference characters 8 and 9 designate the two forward vehicles of a railway train, and the reference characters 10 and 11 designate the two rear vehicles of such train. For example, the vehicles 8 and 9 may be the locomotive and tender of the train, the vehicle 10 may be a freight car, and the vehicle 11 may be a caboose. This particular make-up of train has no significance, however, in so far as my present invention is concerned. The vehicles 8 and 9 are connected by the usual coupler 2, and the vehicles 10 and 11 are likewise connected by similar means.

When my invention is to be utilized for signaling between spaced points on the same train, for example between the locomotive and the caboose, one unit of apparatus embodying my invention may be interposed between the vehicles 8 and 9 at the point A, and another unit embodying my invention may be interposed between ve-

hicles 10 and 11 at point B. These particular locations are not essential, however; as shown in Fig. 2, one unit may be located on the vehicle 8 in advance of the forward axle of the train at the point C, and the other unit may be located on the vehicle 11 in rear of the rear axle of the train at the point D. Inasmuch as the caboose is likely to be operated in each direction, it may be preferable to provide this vehicle with two sets of inductors adjacent the two ends of the vehicle, respectively.

When the forward unit is located in rear of the front axle of the train, and the rear unit is located forward of the rear axle of the train, as illustrated in Fig. 1, each unit will preferably be constructed as shown in Fig. 3. As here shown, the reference characters 3 and 3^a designate magnetizable cores which are mounted on one of the vehicles directly above the track rails 1 and 1^a, respectively, and each of which cores is transversely disposed with respect to the track rails. A third core 4 is also mounted on one of the vehicles in close relation to the coupler 2, and is also disposed transversely with respect to the track rails. Cores 3 and 3^a are provided with windings 5 and 5^a, respectively, and the core 4 is provided with a winding 6. The three windings 5, 5^a and 6 are connected in series, and these windings may be connected either with a generator G of alternating current, or with a signaling device S, through a manually operable circuit controller 7. This circuit controller normally occupies the position in which it is shown in Fig. 3, wherein the three windings are connected with the signaling device S through contact 1-1^a and a suitable filter and amplifier and, if necessary, a demodulator. When the circuit controller 7 is depressed, so that contact 1-1^b is closed, the three windings are disconnected from the signaling device S, and are connected with the generator G.

Each unit may also be provided with suitable means for modulating, at voice frequencies, the current which is supplied to the windings 5, 5^a, and 6 when the switch 7 is depressed. As here shown, this means comprises a transformer T, the secondary 12 of which is interposed in the circuit over which current is supplied to the windings 5, 5^a and 6 from generator G, and the primary 13 of which is connected with a microphone M through a battery 14.

The three windings 5, 5^a and 6 are connected in series in such manner that when the circuit controller 7 is depressed, the currents which are induced in the body of the train and in the track

rails at any instant all flow in the same direction. The track rails and the body of the train in parallel form a closed circuit which is completed through a common path including the track ballast resistance or rail-to-ground impedance and the ground. This is illustrated diagrammatically in Fig. 5. As here shown, the point at which current is induced in the rail 1^a by the flux set up in the core 3^a due to current in the winding 5^a is indicated at P, and the approximate paths taken by this current are illustrated roughly by the broken lines 15 . Similarly, the point at which current is induced in the body of the train is indicated at Q, and the approximate paths taken by this current are indicated roughly by the dotted lines 18 . It should be distinctly understood, however, that this illustration is provided merely for the purpose of indicating that the induced currents flow in a closed circuit including the track rails, the body of the train, rail-to-ground impedance and the ground, and not for the purpose of indicating the current distribution in this circuit. It is apparent, however, from Fig. 5, that the distributed ground current gradually diminishes as the distance from the points P and Q increases and there is a zone extending in both directions from these points within which current of effective magnitude flows, such zone moving with the train. It will be noted that the broken lines 15 form closed loops each of which passes from the point P through the rails to some point on one side of the point P, then through the ballast leakage resistance and the ground to the rails at some point on the other side of the point P, and hence through the rails back to point P. It will also be noted that the dotted lines 18 form closed loops all of which pass through the point Q. It follows, that the current which is induced in the train and in the track rails flows in opposite directions through two sides of a closed circuit, one side of which includes the track rails and the body of the train in both directions from the point of induction, and the other side of which includes the ground. Since the currents induced in the rails and in the body of the train all flow in the same direction at any instant, it follows that the currents which are induced in the windings 5 , 5^a and 6 of the apparatus at the other end of the train by these currents are additive, and the resultant current is amplified to operate signal S.

The operation of the apparatus is as follows: Normally the circuit controller 7 is in such position that contact $7-7^a$ is closed, so that the signaling device S of each unit is connected with the associated windings 5 , 5^a and 6 . Assuming that the engineer wishes to transmit an indication to the occupants of the caboose, he will depress circuit controller 7 , thereby connecting the associated generator G with the inductor windings at the forward end of the train. Currents are thereby induced in the track rails and in the body of the train, and these currents are conducted to the rear end of the train through the track rails and the body of the train in the manner previously described, where they induce currents in the three windings of the unit at point B, and so operate the signaling device in the caboose. The circuit controller 7 may be used as a key to code the transmitted signal, or the engineer may carry on a telephonic conversation by talking into the microphone M. Similarly, an occupant of the caboose may communicate with the engineer by depressing the key 7 of the unit

at point B, whereupon the signal device S on the locomotive will respond.

The signal device S may be of any suitable character, such as a loud speaker, bell, or lamp, or any combination of these devices, depending upon the kind of signals which it is desired to employ. 5

Each of the units is preferably adjusted to impress substantially equal electromotive forces on the two track rails 1 and 1^a and on the coupler 2. 10 The frequency of each generator G may be any suitable value, but is preferably high enough to avoid interference due to currents of commercial or other frequencies. Each filter is, of course, tuned to transmit the frequency of the generator 15 G and to block all other frequencies.

When a unit is mounted in front of the forward axle of the train or in rear of the rear axle of the train, as illustrated in Fig. 2, or when the conductivity of the path through the vehicles and the couplers is comparatively high, the core 4 and winding 6 are unnecessary and may be omitted. Furthermore, under these conditions, each unit may, if desired, be constructed as illustrated in Fig. 4. As here shown, the unit is exactly like the unit illustrated in Fig. 3, except that the windings 5 , 5^a and 6 and the associated cores are replaced by a single winding 17 mounted on a single core 16 located transversely to, and in inductive relation with, both track rails 30 1 and 1^a .

In order to signal between two trains, each of the trains may be provided with one or more units located at any convenient location or locations on the trains. For example, as shown in Fig. 6, each 35 train is provided with a unit located between the locomotive and tender of the train. With this arrangement, if the key 7 of the unit located between the locomotive 8 and tender 9 of the first train is depressed, the resultant currents which 40 are set up in the body of this train and in the track rails will be conducted through the track rails to the second train where they will induce currents in the windings of the unit located between the locomotive 8^a and tender 9^a of this 45 train, and hence operate the signaling device on this train. Similarly, if the key 7 of the unit on the second train is depressed, the signaling device of the unit on the first train will be operated.

When it is desired to signal between a train and a station along the track, the train may be equipped with one or more units in the manner previously described, and another unit or units may be located at some convenient point or points along the track. The unit which is located along 55 the track may, for example, be constructed as illustrated in Fig. 7. As here shown, the unit is exactly like the unit shown in Fig. 4, with the exception that the core 16 and winding 17 of the unit instead of being located on a train above the 60 track rails is located underneath the track rails, and is stationary. The operation of the apparatus under these latter conditions is substantially the same as the operation previously described, and will be readily understood without further 65 description.

It might appear that the operation of apparatus embodying my invention would be interfered with by the insulated joints in the rails of a block signaling system. I have found, however, that 70 the currents induced in the track rails will flow around such insulated joints, either because they pass through the ground, or because of the inherent capacity between the rails at the joints, or both, and that, consequently, the joints will 75

not prevent correct operation of the apparatus. Furthermore, if it is found in some instances that such joints do interfere with the transmission of signal indications from one end of the train to the other, the difficulty may be removed by bridging each insulated joint by a condenser adjusted to conduct the relatively high frequency train signal current but not the current used for the track circuits of the block signal system.

10 Although I have herein shown and described only a few forms of signaling systems for railway trains embodying my invention, it is understood that various changes and modifications may be made therein within the scope of the appended 15 claims without departing from the spirit and scope of my invention.

Having thus described my invention, what I claim is:

1. In combination, a railway train, means located on one vehicle of the train for inducing alternating currents in the body of the train and in the track rails in such manner that the currents flow away from the points at which they are induced in the same direction at any instant and return to the points at which they are induced partly through the ground, and means located on another vehicle of the train and controlled by the currents in the train body and in the track rails due to said first mentioned means.

20 2. In combination, a railway train, means located on one vehicle of the train for inducing in the body of the train and in the track rails alternating currents which at any instant flow away from the point at which they are induced in the same direction and return to the point at which they are induced partly through the ground, means located on another vehicle of the train for inductively receiving a voltage due to said currents in the train body and track rails, means for 25 amplifying said received voltage, and a signaling device actuated by the output of said amplifying means.

3. In a communication system for railway trains, transmitting means located at one point 30 on a train for simultaneously inducing modulated alternating currents in each track rail and in the body of the train all of which currents flow in the same direction at a given instant and return to the points at which they are induced partly through the ground, and signaling means located at another point on the train and responsive to the modulated alternating currents flowing in the train body and track rails due to said transmitting means.

4. Apparatus for signaling between two points 35 on a railway train, comprising three windings located at one point on the train and disposed in inductive relation to the two track rails and a coupler respectively, three windings located at another point on the train and disposed in inductive relation to the two track rails and a coupler respectively, a source of alternating current and a receiving device at each of said points, and manually operable means at each said point for 40 connecting the three said windings with either said source or said receiving device at the same point.

5. Apparatus for signaling between two points 45 on a railway train comprising three windings located at one point on a train and disposed in inductive relation to the two track rails and a coupler respectively, three windings located at another point on the train and disposed in inductive relation to the two track rails and a coupler respectively, means at one of said points

for supplying alternating current to the three said windings in such manner that the currents induced thereby in the track rails and train body all flow in the same direction at any given instant, a receiving circuit located at the other point and including the three said windings connected in such manner that the currents induced therein by the currents in the track rails and train body all flow in the same direction at any given instant, and signaling means controlled by the current in said receiving circuit.

6. Apparatus for signaling between two points on a railway train, comprising three windings located at one point on the train and disposed in inductive relation to the two track rails and a coupler respectively, three windings located at another point on the train and disposed in inductive relation to the two track rails and a coupler respectively, means at one of said points for supplying alternating current to the three said windings in such manner that the currents induced thereby in the track rails and train body all flow in the same direction at any given instant, a receiving circuit located at the other point and including the three said windings connected in such manner that the currents induced therein by the currents in the track rails and train body all flow in the same direction at any given instant, filtering and amplifying means connected with said receiving circuit, and signaling means operated by the output of said filtering and amplifying means.

7. Apparatus for signaling between two points on a railway train, comprising three windings located at one point on the train and disposed in inductive relation to the two track rails and a coupler respectively, three windings located at another point on the train and disposed in inductive relation to the two track rails and a coupler respectively, a source of alternating current and a receiving device associated with each said group of windings, manually operable means at each said point for at times connecting the associated source with the three associated windings in such manner that the currents induced thereby in the track rails and train body all flow in the same direction at any given instant and for at other times connecting the three windings with the associated receiving device in such manner that the currents induced in the windings are additive.

8. Apparatus for signaling between two points on a railway train, comprising three windings located at one point on the train and disposed in inductive relation to the two track rails and a coupler respectively, three windings located at another point on the train and disposed in inductive relation to the two track rails and a coupler respectively, a source of alternating current and a receiving device associated with each said group of windings, manually operable means at each said point for at times connecting the associated source with the three associated windings in such manner that the currents induced thereby in the track rails and train body all flow in the same direction at any given instant and for at other times connecting the three windings with the associated receiving device in such manner that the currents induced in the windings are additive, and filtering and amplifying means interposed between said windings and said receiving device at each said location.

9. Apparatus for signaling between two points on a railway train, comprising three windings located at one point on the train and disposed in inductive relation to the two track rails and a

- coupler respectively, three windings located at another point on the train and disposed in inductive relation to the two track rails and a coupler respectively, a source of high frequency alternating current at one of said points, a circuit at said one point including said source and the three associated windings connected in series in such manner that the currents induced in the track rails and train body by current supplied to the windings over said circuit all flow in the same direction at any given instant, means included in said circuit for modulating the current supplied to the associated windings from said source at voice frequencies, a receiving circuit located at the other point and including the three windings at said other point connected in such manner that the currents induced therein by the currents in the track rails and train body all flow in the same direction at any given instant; filtering, demodulating, and amplifying means connected with said receiving circuit; and signaling means operated by said filtering, demodulating, and amplifying means.
10. In combination, a railway train, means located on the train for inducing in the track rails alternating current which flows in a closed circuit including the rails, the distributed rail-to-ground impedance and the ground, and means located in the trackway and controlled by the currents flowing in the track rails due to said first mentioned means.
11. In combination, a railway train, means located on one vehicle of the train for inducing in the track rails alternating current which flows in a closed circuit consisting of the rails, the distributed rail-to-ground impedance and the ground, and means located on another vehicle of the train and controlled by the current flowing in the track rails due to said first mentioned means.
12. In a signaling system for railway trains; a circuit consisting of the track rails, the distributed rail-to-ground impedance and the ground as a conducting path; a train, transmitting means located along the track for causing a periodic signaling current to flow in said circuit, and receiving means located on a vehicle of the train effectively influenced by such current flowing in said circuit due to said transmitting means.
13. In a signaling system for railway trains; a circuit consisting of the track rails, the distributed leakage conductance of rail to ground and the ground as a conducting path; a train, transmitting means located on a vehicle of the train for causing a periodic signaling current to flow in said circuit, and receiving means located along the trackway effectively influenced by such current flowing in said circuit due to said transmitting means.
14. In a signaling system for railway trains, a train, transmitting means on a vehicle of the train for causing periodic signaling current of effective magnitude to flow in a portion of a track rail both in advance of and to the rear of said vehicle by virtue of a path completed through the rail and the ground and the distributed rail-to-ground impedance, and receiving means effectively influenced by current flowing in said portion of track rail due to said transmitting means.
15. In a signaling system for railway trains, a train; a circuit consisting of the track rails, the rail-to-ground impedance and the ground as the conducting elements; transmitting apparatus mounted on one vehicle of the train and coupled with the track rails to cause a signaling current to flow in said circuit for establishing an effective zone of influence which extends in both directions from said vehicle and moves with the vehicle, and receiving apparatus mounted on another vehicle of the train spaced within such zone and coupled with the track rails for receiving current in response to the current flowing in said circuit due to said transmitting apparatus.
16. In a signaling system for railway trains, a train, a traveling circuit associated with a vehicle of the train; said circuit consisting of a section of the track rails on which an electromotive force is impressed, the track rails extending in both directions from the vehicle, the rail-to-ground impedance and the ground as a conducting path; transmitting apparatus mounted on said vehicle and coupled with the track rails for producing the electromotive force in said circuit, receiving apparatus mounted on another vehicle of the train and coupled with the track rails for receiving an electromotive force in response to the current flowing in said circuit due to the electromotive force produced by said transmitting apparatus, and signaling devices effectively influenced by such received electromotive force.
17. In a signaling system for railway trains, a train; transmitting apparatus located on one vehicle of the train and coupled with the track rails to cause a periodic signaling current to flow in a circuit including the track rails on one side of said vehicle, the distributed rail-to-ground impedance on said one side of the vehicle, the ground path, the distributed rail-to-ground impedance on the other side of said vehicle and the rails on said other side of the vehicle; said circuit having an effective zone which extends along the track in both directions from said vehicle and which moves with the vehicle, and receiving apparatus located on a second vehicle of the train spaced within such zone and coupled with the track rails for receiving current in response to the current flowing in said circuit due to said transmitting apparatus.
18. In a signaling system for railway trains, a train, transmitting apparatus located on a vehicle of the train and including a source of periodic signaling current, circuit elements connected with said apparatus and coupled with the track rails to create in the rails adjacent said vehicle an electromotive force which causes the potential of the rails to vary with respect to ground potential, said varying potential effective to cause such signaling current of effective magnitude to flow in a portion of the rails both in advance of and to the rear of said vehicle by virtue of the distributed rail-to-ground impedance and the ground as a conducting path, receiving apparatus including a signal device responsive to such current, and circuit elements connected with the receiving apparatus and coupled with the track rail along said portion of the track rail for effectively influencing said device in response to the current flowing in the rail due to said transmitting apparatus.
19. In a signaling system for railway trains, a train; a circuit consisting of the track rails, the rail-to-ground impedance and the ground as the conducting elements; transmitting apparatus and receiving apparatus mounted on each of two vehicles of the train, said transmitting apparatus each including a source of periodic signaling current to cause such current to flow in said circuit for establishing an effective zone of in-

fluence which extends in both directions from the associated vehicle, said two zones thus established overlapping and moving with the train, said receiving apparatuses each including a signaling device responsive to such current flowing in said circuit due to the transmitting apparatus of the other vehicle, and means on each of said vehicles for selectively governing its apparatuses to effect two-way signaling between said vehicles by virtue of said circuit.

20. In a signaling system for railway trains, a train, stretch of track which is divided for way-side signaling purposes into sections by insulated rail joints, transmitting apparatus located on one vehicle of the train and including a source of periodic communication current, means to couple the transmitting apparatus with the track rails to cause such communication current to flow in the track rails both in advance of and to the rear of said vehicle by virtue of the distributed rail-to-ground impedance, and to flow around an insulated joint by virtue of the capacitance and the leakage conductance between the rail sections near the insulated joint, receiving apparatus located on another vehicle of the train and including a device responsive to such communication current, and means to couple said receiving apparatus with the track rails for effectively influencing said device in response to current flowing in the rails due to said transmitting apparatus.

21. In a signaling system for railway trains, a train; transmitting apparatus mounted on one vehicle of the train including a generator of carrier current, a telephone transmitter for modulating the carrier with voice frequencies and means for delivering the carrier telephone current to the track rails; receiving apparatus mounted on another vehicle of the train responsive to such telephone current and including means for receiving current from the track rails, said generator proportioned to generate a carrier frequency which is above the highest voice frequency to be transmitted so that interference from commercial power frequencies is reduced but which is sufficiently low to be substantially free from electromagnetic wave radiation and for which frequency the rail impedance is sufficiently low that said transmitting apparatus is effective to cause current of a given magnitude to flow in the rails both in advance of and to the rear of said one vehicle for approximately a freight train length by virtue of the rail-to-ground leakage conductance and the ground as a conducting path, and said receiving apparatus proportioned to be effectively influenced by such current of said given magnitude.

22. In a signaling system for railway trains; a circuit consisting of the track rails, the rail-to-ground leakage conductance and the ground; transmitting apparatus mounted on the train including a generator of carrier current, a telephone transmitter for modulating the carrier with voice frequencies and means for producing in the rails an electromotive force corresponding to such modulated carrier; said generator being proportioned to deliver a carrier of a frequency outside of the radio communication band and for which frequency the rail inductance bears such a relation to the leakage conductance to ground that said electromotive force is effective by virtue of said circuit to cause current of a given magnitude to flow in the rails for a distance of the order of magnitude of one mile

extending in both directions from the point at which such electromotive force is produced, and receiving apparatus including means coupled with the rails within such distance effectively influenced by such current of said given magnitude.

23. In a signaling system for railway trains, a train; transmitting apparatus mounted on one vehicle of the train including a generator of carrier current, a signaling transmitter for modulating the carrier with a predetermined frequency and means for delivering the carrier signaling current to the track rails; receiving apparatus mounted on another vehicle of the train responsive to such signaling current and including means for receiving current from the track rails, said generator proportioned to generate a carrier frequency that is high enough that interference from commercial power frequencies is substantially avoided but which is sufficiently low to be substantially free from electromagnetic wave radiation and for which frequency the rail impedance is sufficiently low that said transmitting apparatus is effective to cause current of a given magnitude to flow in the rails both in advance of and to the rear of said one vehicle for a distance of the order of magnitude of one mile by virtue of the rail-to-ground leakage conductance and the ground as a conducting path, and said receiving apparatus provided with an amplifier so as to be effectively influenced by current of said given magnitude.

24. In a signaling system for railway trains, transmitting apparatus on one vehicle of a train, including a conductor coupled with one, at least, of the usual track rails of the track to produce an electromotive force in the rail for causing a periodic difference of potential between points in the rail in advance of and to the rear of said vehicle, and receiving apparatus on another vehicle of the train including an amplifier and a conductor coupled with said rail, said track rail where extending beyond said one vehicle constituting an indefinitely extended open end conductor with a maintained though gradually diminishing difference of potential to cause distributed ground currents to flow through the leakage conductance, a fraction of which current affects the conductor of said receiving apparatus.

25. In a signaling system for railway trains, transmitting apparatus on one vehicle of a train including a source of periodic signaling current, receiving apparatus on another vehicle of the train including an amplifier, an open metallic circuit including a track rail as a conductor extending along the right-of-way and disposed for relatively low leakage conductance which is substantially uniformly distributed throughout the length of the track rail, means to couple said transmitting apparatus to said track rail to set up an electromotive force in said track rail for producing a current in the track rail by virtue of said distributed leakage conductance, said current gradually diminishing in magnitude as the distance is increased from the point where the electromotive force is set up, and means to couple the receiving apparatus to said track rail for impressing on the amplifier of said receiving apparatus an electromotive force due to distributed current to ground which flows in the track rail beyond the inter-vehicle section at the receiving end and returns beyond such section at the transmitting end.

LARS O. GRONDAHL.
